UNITED STATES PATENT OFFICE.

JACOB G. PECK, OF PORTLAND, OREGON.

TWO-TEMPERATURE REFRIGERATING AND COOLING CABINET.

Application filed August 5, 1925. Serial No. 48,377.

One of the objects of this invention, consists in a new, novel, and useful improvement in a two compartment cabinet, wherein in articles of merchandise may be maintained in each compartment and each adapted to having a different temperature maintained therein.

A further object of my invention consists, in a hinged closure wherein access may be had to each compartment from either side of the cabinet.

A further object of my invention consists in a thin cooling medium tank being disposed about the vertical side and end walls of each compartment, adapted to the maintaining of the cooling medium therein and the passage therethrough of an expansion coil for maintaining low temperatures in each compartment, the temperatures in one of the compartments to be maintained at a lower temperature than in the other.

Still further objects of my invention, consist in the construction of a cabinet that may be produced in quantity production in a central plant and shipped to the point of use, wherein all parts are interchangeable and a minimum of space may be occupied by the cabinet with a maximum of storage capacity in each of the compartments to be refrigerated.

A further object of my invention consists in the construction and arrangement of the cooling medium tanks within the compartments for the maintaining of the cooling medium therein, the tanks to form the vertical side and end walls of the compartments to be refrigerated.

Still further objects of my invention, consists in the cooling medium being adjacent the vertical side walls of the compartment only, with no cooling medium being disposed below the surface of the bottom of the compartment to be refrigerated.

Still further objects of my invention, consist in the detailed construction of the cabinet, wherein a refrigerated two compartment cabinet is constructed having its outer surfaces made out of suitable material as plywood or veneer, and having a top closure through which admission may be had into each compartment from either side of the cabinet.

With these and incidental objects in view, the invention consists in certain novel features of construction and combination of parts, the essential elements of which are set

forth in the appended claims and to a preferred form of embodiment of which is hereinafter shown with reference to the drawing which accompany and form a part of this specification.

In the drawings:—

Fig. 1 is a perspective view of the completed cabinet, with the side walls partially broken away to illustrate the construction of the cabinet.

Fig. 2 is a transverse cross sectional view, of the cabinet.

Fig. 3 is a cross sectional view, taken on line 3—3 of Fig. 2, looking in the direction indicated, the same being of the high temperature compartment of the cabinet.

Fig. 4 is a cross sectional view, taken on line 4—4 of Fig. 2, looking in the direction indicated, the same illustrating and being the low temperature compartment of the cabinet.

Fig. 5 is a detailed plan view of one preferred embodiment of the lid closures.

Fig. 6 is a partially perspective sectional view, of one unit only, of the lid closures, as illustrated in Fig. 5.

Fig. 7 is a partial end view of one of the lid closures, made to illustrate the hinge mechanism of the same.

Fig. 8 is a partial cross sectional view of the two temperature cabinet, made to illustrate the frame construction of the same.

Fig. 9 is a perspective elevation of a part of one corner, partially in section, made to illustrate the joinery used in the fabricating of the frame.

Fig. 10 is a partial cross sectional view, of the cooling medium tank.

Like reference characters refer to like parts throughout the several views.

1 is the cabinet. I first form a frame structure composed of posts 29, to which are secured side and end rails 30, the same being framed together and secured by suitable fastenings, as screws and glue, or by any other suitable fastening means after which an outer ply wood or veneer covering is placed, the same being finished in any suitable manner to resist the character of usage for which the cabinet is to be used as by shellac or any high grade moisture resisting varnish. A high temperature compartment 2, and a low temperature compartment 3, are disposed within the cabinet, access into each of which may be had through an insulated lid closure disposed and fitted

to the entrance to the compartments through the top of the cabinet; surrounding each compartment is a cooling medium tank adapted to the circulation of a cooling medium therein. The tank 4, in the high temperature compartment does not extend the full depth of the compartment and finishes on its inner side walls in a vertical straight line, as shown at 5, the refrigerant material 10 passing around the upper portion of the compartment. The tank 6 in the low temperature compartment, extends for practically the full distance of the inner, vertical walls and entirely surrounds the vertical side 15 and end walls of the compartment, as shown at 7; the outer walls of the cooling medium tank 6, finish in a straight line for the entire depth of the compartment. The bottom of each compartment, as shown at 8, 20 does not have a refrigerant circulated thereunder.

In the construction of my cabinets, I first lay a full layer of insulating material, as 25 9, entirely across the bottom 10, of the cabinet. I then place the side walls 11, of the insulating material, after which I lay a second layer 12, entirely across the bottom, after which I place a second layer 13, of the side walls. The end wall layers are then 30 placed, as shown at 14, the same being placed at either end of the compartment and across the central section dividing the cabinet into two separate and distinct compartments. The metallic pans 8, are then placed in 35 each compartment. The cooling medium tanks are then placed therein, after which the top insulating material is placed. The top of the cabinet 15 may then be placed, and secured in position by any suitable fastening means, as screws, or if it is desirable 40 to place the expansion coils within the cooling medium tanks first, the same may be done; these expansion coils are not shown herein, as the same may be placed after the delivery of the two temperature cabinet 45 to the user, or the distributor of the same. It will be noted that in the high temperature compartment, that the cooling medium tank is disposed about the upper portion 50 of the tank; in my construction I form these cooling medium tanks in depth slightly more than the outer diameter of the expansion coil, thus reducing the amount of cooling medium to a minimum to be used. A third 55 layer of insulating material 16, is placed below the cooling medium tank in the high temperature compartment. Cross bars 17, are placed on the larger compartment for hinging the closures 18 and 19, therein; 60 handles 20 and 21 being provided to facilitate the raising and lowering of the closures. Hinge members 22, are provided upon the closure, and which are secured to the closure, by suitable fastening means, as screws. 65 These hinges have projecting lugs 23, adapt-

ed to engagement with the cross members 17 in slots 24, provided for that purpose.

In the smaller compartments, a double closure 25, is split transversely its length and hinged at its meeting edges, as shown at 70 26, a handle member 27, being provided to facilitate the movement, and the raising of the same. This split hinged member is not secured to the cabinet and may be lifted off entirely when desired for the admission of 75 heavy articles to be placed therein, as ice cream cans. Legs 28, are disposed upon the lower portion of the cabinet to prevent the same sitting flatly upon the supports, as the floor, where the same is to be used, as a 80 certain amount of moisture is present at all times. These legs permit of an air circulation beneath and around the cabinet. A frame structure of posts 29, and side and end rails 30, is provided for strengthening the 85 cabinet. The outer covering of the same being preferably formed of ply wood, or laminated material, which is properly treated on the outside to prevent warping and becoming saturated with the liquids being used 90 thereabout or therearound. The posts, side and end rails are mortised, as shown in detail in Fig. 9, to form a strong and uniform frame structure, sufficiently strong to maintain the weight of the cabinet. 95

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow. 100

What I claim is:—

1. A new and improved two temperature refrigerating and cooling cabinet, comprising a frame structure, suitable material to form the exterior covering and floor of said frame structure, two compartments formed in said cabinet, there being an opening there-to through the top of said cabinet; cooling medium tanks about said compartments and forming the walls thereof, pans to form the floors of said compartments, and insulating material between the covering and the sides of the cooling medium tanks, and between the floor of said cabinet and said pans, the tanks in one compartment being of greater depth than those of the other compartment whereby to provide different temperatures in the two compartments. 110 115 120

2. A two temperature refrigerating and cooling cabinet comprising an outer casing suitably lined with heat insulation and enclosing two compartments of approximately equal depth, cooling medium tanks located within and about each compartment, the inner walls of which tanks comprise the inner walls of said compartments, pans on the 125

bottom of said compartments constituting floors into which pans, adjacent their margins, the tanks are set, the tanks of one compartment being of less depth than those of the other compartment, and the pan of said one compartment having a depressed or dished portion extending from the bottom of said tanks in alignment with the inner walls thereof down to the bottom of the compartment, the outline of the vertical portion of the wall of said dished portion of the pan and the outline of the inner wall of the tanks of said one compartment lying in alignment with each other substantially as shown. 10

JACOB G. PECK.
